WILLIAM R. BURKE, OF UTICA, NEW YORK, ASSIGNOR TO SIGNAL ACCESSORIES CORPORATION, OF UTICA, NEW YORK, A CORPORATION OF NEW YORK.

SOLDERLESS BOOTLEG TERMINAL CONNECTER.

Application filed October 31, 1927. Serial No. 230,025.

This invention relates to a "solderless bootleg terminal connector" for electric conductors adapted to be used more particularly in connection with the installation and operation of electric railway signals and other instruments having electrical connection with a track rail or analogous conductor for securing and maintaining a more perfect and permanent electric connection between the wire cable and rail.

The main object is to provide a terminal connector of this character by which a solid or stranded wire cable may be easily and expeditiously connected to a railway rail or analogous conductor to form a more perfect and permanent electric connection therewith without the use of solder or other fusible material and at the same time to reduce to a minimum the liability of loosening of the connection by the vibrations of the rails incidental to the movement of the rolling stock along and upon the rails.

One of the specific objects is to seat the terminal end of the conducting wire in a lengthwise groove in the periphery of a tapered pin and then to insert the tapered pin with the terminal end of the wire in the groove into a tapered socket of the connector so that the wire will be wedged between the tapered pin and adjacent wall of the socket, and the walls of the socket expanded against the walls of the opening in the rail as the tapered pin is driven into the socket, thereby securing a more perfect electric contact between the tubular head and rail and also between a wire terminal and tubular head.

One of the specific objects is to provide the tubular head with a lateral elongated shank or tang having opposed terminal jaws bendable towards each other for firmly gripping the periphery of the insulated portion of the wire to relieve the strain upon the joint between the wire and the tubular head resulting from the vibrations of the rail.

Other specific objects and uses relating to any specific parts of the device will be brought out in the following description:

In the drawing:—

Figure 1, is a side elevation of a railway rail and electric conductor showing my improved terminal connector in operative position for connecting the wire conductor or cable to the rail.

Figure 2, is an enlarged longitudinal sec-

tional view taken in the plane of line 2—2, 55 Fig. 1.

Figure 3, is a transverse sectional view through a portion of a connector taken on line 3—3, Figure 1.

Figures 4, and 5, are perspective views of 60 the detached parts of the coupling or connector.

In order that one adaptation of my invention may be clearly understood I have shown a railway rail —A— as provided with a 65 cylindrical bore or opening —a— through the web thereof, receiving a cylindrical tubular head —1— of my improved coupler or terminal connector.

The head —1— is provided with a laterally 70 elongated radial extension —2— of suitable metal having opposed bendable jaws —3— some distance from the tubular head —1— and normally open to form a lengthwise 75 groove —4— which is substantially radial to the axis of the tubular head —1—.

The tubular head —1— projects laterally from one end of the shank or tang —2— to one side thereof, while the jaws —3— project from the opposite edges of the other end 80 of the shank or tang —2— to the opposite side thereof so that when the tubular head is inserted in the opening —a— in the rail the opposite side of the groove —4— and jaws —3— will face outwardly.

The periphery of the tubular head —1— is made cylindrical to correspond to the diameter of the opening —a— in the rail so as to fit snugly in said opening when inserted therein.

The central opening as —5— in the tubular head —1— is tapered from the proximal end of the side of the head adjacent the shank —2— toward the distal end of the head, for receiving a similarly tapered pin or wedge-key —6— which when driven into the opening —5— serves to slightly expand the distal end of the tubular head —1— against the walls of the opening —a— in the rail, for firmly holding the tubular head in operative 95 engagement with the rail and at the same time forming a close electrical contact therewith.

The tapered pin or wedge —6— is provided with a lengthwise groove —7— in its periphery extending from end to end thereof for receiving the terminal end as —8— of an electric conductor or wire —9— shown more

clearly in Figure 2. This electric conductor —9— may be of the solid wire or stranded wire type and aside from the terminal end —8— is preferably covered with suitable insulation —10— adapted to extend along and upon the outer face of the shank or tang —2— and through the groove —4— between the jaws —3—.

The radial depth of the groove in the periphery of the tapered key —6— is somewhat less than the diameter of the terminal end —8— of the conductor —9— to permit contact of side terminal end —8— with the adjacent wall of the tapered opening —5—.

15 The base or bottom of the groove —7— is disposed at an angle to the axis of the tapered key —6— and substantially parallel with the outer lengthwise edges of the walls of the groove —7— so that the portion of the tapered key —6— opposite the open side of the groove —7— will be also tapered from its proximal end toward its distal end, for exerting a wedging action against the terminal end —8— of the conductor —9— to force end —8— of the conductor —9— to force 20 said conductor firmly against the opposite wall of the tubular head when the tapered key —6— is driven into the tapered socket —5—.

When the terminal —8— of the conductor 30 —9— and tapered key —6— are assembled in the socket —5— of the tubular head —1— and the latter is inserted into the opening —a— in the web of the rail —A— a substantially perfect electric contact will be established 35 between the terminal end —8— of the conductor and tubular head —1— and also between the tubular head and rail —A—, it being understood that the tapered key —6— also forms a substantially perfect electric 40 connection with the terminal —8— and the tubular head —1—.

The insulated portion of the conductor —9— extends along the outer surface of the tang —2— for connection with electric signals or other electric appliance commonly used in connection with railways and after it is properly seated between the jaws —3— the latter are bent towards each other and against the periphery of the insulation —10— as shown in Figure 3, to grip and firmly hold the conductor —9— against movement relatively to the shank or tang —2—.

Operation.

55 The cylindrical portion of the head —1— at one side of the tang —2— is first inserted in the cylindrical opening —a— in the web of the rail —A— after which the terminal end —8— of the conductor —9— is inserted in end —8— of the conductor —9— is inserted in 60 the socket —5— and then the tapered key —6— is placed in operative position within the socket —5— with its groove registering with the terminal end —8—, following which the tapered key —6— is driven tightly in place 65 by application of suitable force to its proximal

or large end, thereby firmly establishing a close electrical connection between the tapered pin —6— and terminal end —8—, and also between the tapered pin —6— and the tubular head —1—, and at the same time 70 slightly expanding the tubular portion of the head against the wall of the opening —a— in the web of the rail to further perfect the electric connection between said head and rail. 75

The conductor —9— with the insulation —10— is then extended along and against the outer face of the tang —2— and firmly clamped in place by the inward bending of the free edges of the jaws —3— against the periphery of the insulation —10—.

When the conductor —A— and —9— are firmly connected in the manner described, the distal ends of the key —6— and wire terminal —8— may be severed and finished 85 off substantially flush with the adjacent face of the rail if desired.

What I claim is:

1. A solderless bootleg terminal connector for electric conductors comprising a tubular head adapted to be inserted in an opening in one conductor and provided with a laterally extending tang having bendable jaws adapted to be closed upon the periphery of another conductor, and a wedge inserted into the tubular head and provided with a lengthwise groove for receiving a portion of the second named conductor and wedging the same against the adjacent wall of the tubular head. 90

2. The combination with the web of a rail-way rail having a cylindrical opening there-through, a cylindrical head fitted in the opening and provided with a central lengthwise opening tapered from its proximal end toward its distal end, a tapered pin inserted 100 into the opening in the head, and provided with a lengthwise groove in its periphery for receiving a portion of an electric conducting cable and a tang secured to and projecting laterally from the proximal end of the head 105 and provided with bendable jaws for gripping the periphery of said cable. 110

3. A terminal connector for electric conductors comprising a tubular head adapted to be inserted in an opening in one conductor, and a tapered pin inserted into the tubular head and having a lengthwise groove in its periphery for receiving a portion of another conductor, said groove being of less radial depth than the thickness of the conductor to cause the adjacent portion of the latter to impinge against the adjacent wall of the opening in the head as the pin is driven into said opening, said head being provided with a radially projecting tang having opposed 120 bendable jaws for gripping the periphery of the second-named conductor. 125

In witness whereof I have hereunto set my hand this 17th day of October, 1927.

WILLIAM R. BURKE.
